UNITED STATES PATENT OFFICE.

CHARLES SMALLWOOD, OF EASTMAN, GEORGIA.

METALLIC SHINGLE.

Application filed December 14, 1921. Serial No. 522,261.

To all whom it may concern:

Be it known that I, CHARLES SMALLWOOD, a citizen of the United States, residing at Eastman, in the county of Dodge and State 5 of Georgia, have invented a new and useful Metallic Shingle, of which the following is a specification.

This invention relates to roofing and more particularly to a novel form of metallic 10 roofing sheet employed for forming a roof, the sheet being especially designed so that adjacent edges thereof may be interlocked to secure the sheets together.

Another object of the invention is to provide 15 a lock joint of this construction to permit the sheets to be laid, or positioned to simulate a shingled roof.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 is a fragmental plan view of 30 a roof formed of a number of sheets constructed in accordance with the present invention.

Figure 2 is a sectional view taken on line 2-2 of Figure 1.

Figure 3 is a sectional view taken on line 35 3-3 of Figure 1.

Figure 4 is a perspective view of the under side of a sheet.

Referring to the drawing in detail, the 40 sheet forming the essence of this invention includes a body portion 5, which may be formed of suitable flexible sheet metal, one edge thereof being formed into a tubular portion 6 to provide a securing flange. The 45 opposite edge of the body portion 5 is curved upwardly as at 7 where the same is curved downwardly as at 8 to provide a flange de-

signed to interlock with the flange 6 of the adjacent sheet.

As clearly shown by Figure 4 of the drawing, a portion of the upwardly and downwardly curved flange is cut away as at 9 to permit the adjacent upper sheet to be moved downwardly with respect to the sheet supported therebelow, so that the adjacent upper sheet will overlap the connection between adjacent upper and lower sheets.

The curved portion 8 terminates in a relatively straight flange 10 adapted to rest on the roofing proper, the flange being provided with suitable openings to accommodate securing nails. Thus it will be seen that when it is desired to position sheets constructed in accordance with the present invention, the 65 tubular portion 6 of one sheet, and which extends above the roof surface, is positioned within the curved portion 8 of the adjacent sheet, and the sheet is then moved downwardly to cause the same to closely engage 70 the roof.

When the sheet is moved downwardly into engagement with the roof, it will be seen that the portion of the curved portion 8 adjacent to the curved portion 7 is moved into 75 close engagement therewith, making a fluid-tight connection at this point.

Having thus described the invention, what is claimed as new is:

In a shingle of the class described, a body 80 portion having its lateral edges rolled, one of the rolled edges overlying the body portion, the opposite rolled edge being rolled outwardly from the body portion of the shingle and inwardly upon itself within the said roll, the last mentioned rolled portion being cut away throughout a portion of its length, and the free edge of the last mentioned rolled portion extending in the plane 85 of the body portion to provide an attaching 90 flange.

In testimony that I claim the foregoing as my own, I have hereto affixed my signature.

CHARLES SMALLWOOD.
